US00D785656S

(12) **United States Design Patent** (10) Patent No.: **US D785,656 S**
 Bramer et al. (45) Date of Patent: ** May 2, 2017

(54) **DISPLAY SCREEN OR PORTION THEREOF WITH GRAPHICAL USER INTERFACE**

(71) Applicant: **Meditech International Inc.**, Toronto (CA)

(72) Inventors: **Richard Barrett Bramer**, Toronto (CA); **Mark Anthony Slonchka**, Brampton (CA)

(73) Assignee: **Meditech International Inc.**, Toronto (CA)

(**) Term: **15 Years**

(21) Appl. No.: **29/546,633**

(22) Filed: **Nov. 24, 2015**

(51) LOC (10) Cl. **14-04**

(52) U.S. Cl.

USPC **D14/486**; D14/495

(58) **Field of Classification Search**

USPC D14/485-495
 CPC .. G06F 3/04842; G06F 19/34; G06F 19/3418;

(57) **CLAIM**

The ornamental design for a display screen or portion thereof with graphical user interface, as shown and described.

DESCRIPTION

The FIGURE is a front view of a display screen or portion thereof with graphical user interface.

The broken line showing of the display screen or portion thereof and portions of the graphical user interface are included for the purpose of illustrating environmental structure and portions of the article and form no part of the claimed design.
